(57) **ABSTRACT**

This invention is a new and distinct grapevine variety named 'IFG Fourteen' which is characterized by producing small round bright red berries having very crisp texture with a very strong muscat flavor and which ripens in midseason.

1 Drawing Sheet

1

Latin name of the genus and species claimed: *Vitis vinifera*.
Variety denomination: 'IFG Fourteen'.

BACKGROUND OF THE INVENTION

The new and distinct grapevine described and claimed herein originated from a hand pollinated cross of the IFG 01077-096-221, an unnamed seedless selection from the IFG breeding program and the IFG 01054-082-202 another unnamed seedless selection from the IFG breeding program hybridized in May 2004. The abortive seed traces were subsequently embryo cultured and the resulting plant was planted in the field in April 2005. The present variety of grapevine was selected as a single plant in 2006 and was first asexually propagated by hardwood cuttings in December 2006 near Delano, Kern County, Calif. The resulting propagules were planted during April 2007 near Delano, Kern County, Calif. and were found to reproduce true-to-type through at least two generations of asexual reproduction using hardwood cuttings and grafting onto rootstocks.

BRIEF SUMMARY OF THE INVENTION

The new grapevine 'IFG Fourteen' is characterized by producing small round bright red berries having very crisp texture with a very strong muscat flavor and which ripens in midseason. Berries are borne on small to medium size clusters which are very compact and require gibberellin applications to thin clusters and size berries. Berries color extremely well and do not require chemical applications to achieve good color. 'IFG Fourteen' stores extremely well. Stems remain green and berries retain their crisp texture and strong muscat flavor for up to twelve weeks in cold storage. To the inventor's knowledge, the known variety to which the new grapevine variety is most similar is the Flame seedless variety (unpatented). 'IFG Fourteen' differs from the 'Flame Seedless' by ripening approximately three to four weeks later, having less waxy bloom and having a very strong flowery muscat flavor as opposed to the neutral flavor of 'Flame Seedless'.

2

'IFG Fourteen' differs from its maternal parent by producing brighter red, crisp berries that have a strong muscat flavor as opposed to the softer reddish black later ripening neutral flavored fruits of the IFG 01077-096-221. It differs from its pollen parent, by having later ripening, crisp red, muscat flavored berries as opposed to the early ripening black berries of the IFG 01054-082-202.

10 BRIEF DESCRIPTION OF THE FIGURE

The accompanying photographic illustration in FIG. 1 illustrates in full color 'IFG Fourteen'. The colors are as nearly true as is reasonably possible in a color representation of this type.

**15 DETAILED BOTANICAL DESCRIPTION OF THE
INVENTION**

Throughout this specification, color names beginning with a small letter signify that the name of that color, as used in common speech, is aptly descriptive. Color names beginning with a capital letter designate values based upon R.H.S. 20 Colour Chart, published by The Royal Horticultural Society, London, England.

Throughout this specification subjective description values conform to those set forth by the International Plant Genetic 25 Resources Institute publication 'Descriptors for Grape' (*Vitis* spp.) (1983) which was developed in collaboration with the Office International de la Vigne et du Vin (OIV) and the International Union for the Protection of New Varieties of Plants (UPOV).

30 The descriptive matter which follows pertains to 'IFG Fourteen' plants grown in the vicinity of Delano, Kern County, Calif. during 2009, and 2010 and is believed to apply to plants of the variety grown under similar conditions of soil 35 and climate elsewhere:

VINE

General:		Young leaves:
Size.—Medium.		<i>Color of upper surface of first four distal unfolded leaves.</i> —Green-Copper.
Vigor.—Medium to slightly weaker than average.	5	<i>Average intensity of anthocyanin coloration of six distal leaves prior to flowering.</i> —Weak.
Density of foliage.—Medium dense.		<i>Density of prostrate hairs between veins (lower surface)</i> —Sparse.
Productivity.—Very productive.		<i>Density of prostrate hairs on veins (lower surface).</i> —Sparse.
Root stock.—Own root.		<i>Density of erect hairs between veins (lower surface).</i> —Sparse to Medium.
Training method.—Typically spur pruned leaving 2 bud spurs.	10	<i>Density of erect hairs on veins (lower surface).</i> —Sparse.
Trunk:		Mature leaves:
<i>Trunk diameter of 4-year-old vines at 30 cm above the soil line.</i> —4.8 cm.		<i>Average length.</i> —About 14.2 cm.
Shape.—Medium stocky.	15	<i>Average width.</i> —About 18.3 cm.
Straps.—Short-Split.		<i>Mature leaf size.</i> —Medium.
Surface texture.—Smooth.		<i>Shape of blade.</i> —Pentagonal.
Inner bark color.—Can be any of the following colors; 165A, 164A, and 177C.	20	<i>Number of lobes.</i> —5.
SHOOTS		<i>Anthocyanin coloration of main veins on upper side of blade.</i> —Absent.
Young shoot:		<i>Mature leaf profile.</i> —Undulate.
<i>Form of tip.</i> —Wide open.		<i>Blistering surface of blade upper surface.</i> —Weak.
<i>Distribution of anthocyanin coloration of tip.</i> —Absent.	25	<i>Leaf blade tip.</i> —Curved downwardly.
<i>Intensity of anthocyanin coloration of tip.</i> —Absent.		<i>Undulation of margin.</i> —Pronounced.
<i>Density of prostrate hairs of tip.</i> —Medium.		<i>Thickness.</i> —Medium.
<i>Density of erect hairs of tip.</i> —Absent.		<i>Undulation of blade between main and lateral veins.</i> —Overall.
Color.—Yellow-Green; can be any of the following colors; 153A and B, and N144A.	30	<i>Shape of teeth.</i> —Mixture of both sides straight and both sides convex.
Woody shoots (mature canes):		<i>Length of teeth.</i> —Short.
Shape.—Medium.		<i>Ratio length/width of teeth.</i> —Small.
Internode length.—Short to Medium; About 6.9 cm.		<i>Shape of upper lateral sinuses.</i> —Lobes strongly overlapping.
Width at node.—About 1.3 cm.		<i>Depth of upper lateral sinuses.</i> —Medium.
Cross section.—Elliptic.	35	<i>General shape petiole sinus.</i> —Lobes half overlapping.
Surface.—Striate.		<i>Shape of base of upper leaf sinuses.</i> —U-shaped.
Main color.—Yellowish-brown; can be any of the following colors; 166C and D, 164A and B, and 165B and C.		<i>Tooth at petiole sinus.</i> —Absent.
<i>Density of erect hairs of nodes.</i> —None.	40	<i>Density of prostrate hairs between veins on lower surface of blade.</i> —Sparse.
<i>Density of erect hairs on internodes.</i> —None.		<i>Density of erect hairs between veins on lower surface of blade.</i> —Medium.
<i>Growth of axillary shoots.</i> —Weak; Approximately 12.0 cm.		<i>Density of prostrate hairs on main veins on lower surface of blade.</i> —Sparse.
Flowering shoot:		<i>Density of erect hairs on main veins on lower surface of blade.</i> —Sparse-Medium.
<i>Vigor during flowering.</i> —Medium.	45	<i>Density of prostrate hairs on main veins on upper surface of blade.</i> —Sparse.
<i>Attitude during flowering on shoots not tied.</i> —Semi-erect-Horizontal.		<i>Density of erect hairs on main veins on upper surface of blade.</i> —None.
Color.—Dorsal side of internodes — Green.		<i>Autumn coloration of leaves, leaves can be a single color or combination of colors in a mottled pattern or on the edges of the leaves.</i> —Yellow-Green; 153A, Grey-Red; 178A and B, Grey-Purple; 183A and B, Grey-Orange; 163A and B.
Color.—Ventral side of internodes — Green.		
Color.—Dorsal side of nodes — Green.	50	
Color.—Ventral side of nodes — Green.		
<i>Density of prostrate hairs of nodes.</i> —None-Very sparse.		
<i>Density of erect hairs of nodes.</i> —None.		
<i>Density of prostrate hairs on internode.</i> —Very sparse.		
<i>Density of erect hairs on internode.</i> —None.	55	
<i>Anthocyanin coloration of buds.</i> —Absent.		
Tendrils:		Upper surface:
<i>Distribution on the shoot (at full flowering).</i> —Discontinuous.		<i>Color.</i> —Green; leaves can be any one of the following colors, depending on their location in the plant canopy; 146A and B, and 137B.
Length of tendril.—Medium; About 22.3 cm.	60	<i>Anthocyanin coloration of main veins.</i> —Absent.
Thickness.—Medium.		<i>Surface appearance.</i> —Glossy to Semi-glossy.
Color.—Yellow-Green; can be any of the following colors; N144A, 144B, and 154A.		<i>Blistering surface of blade.</i> —Weak to Medium.
Form.—mostly bifurcated, occasionally trifurcated or quadfurcated.		
Number of consecutive tendrils.—2.		

LEAVES

Lower surface:

Color.—Green: leaves can be any one of the following colors, depending on their location in the plant canopy; 146A and B.

Anthocyanin coloration of main veins (lower surface).—Absent.

Glossiness.—Medium.

Surface texture.—Smooth.

Surface appearance.—Semi-glossy.

Petiole:

Length.—About 16.8 cm.

Length of petiole compared to middle vein.—Slightly longer.

Density of prostrate hairs on petiole.—Sparse.

Density of erect hairs on petiole.—None.

Buds:

Bud fruitfulness.—Basal: Mostly fruitful.

Position of first fruitful shoot on previous season cane.—1st to 2nd node.

Time of bud burst.—Early; Feb. 18, 2010.

FLOWERS

General:

Flower sex.—Hermaphrodite.

Length of first inflorescence.—Medium; About 20.8 cm long by 8.2 cm wide.

Position of first flowering and fruiting node.—2nd to 3rd (current season growth).

Number of inflorescence per flowering shoot.—1.1 to 2.

Time of bloom.—Midseason as compared with similar varieties in the growing area of Delano, Calif.

Date of full bloom.—May 18, 2010.

FRUIT

General:

Ripening period.—Early; Approximately Aug. 9, 2010.

Use.—Fresh market.

Keeping quality.—Excellent, stores for up to 12 weeks.

Resistance to.—Insects: Average typical of *Vitis vinifera* species. Diseases: Average typical of *Vitis vinifera* species.

Shipping quality.—Excellent.

Refractometer test.—Solid-sugar: About 18.0 Brix.
